US00D790549S

(12) **United States Design Patent** (10) **Patent No.:** **US D790,549 S**
(45) **Date of Patent:** **** Jun. 27, 2017**

(54) **COMPONENT FOR AN ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/566,212**

(22) Filed: **May 27, 2016**

OTHER PUBLICATIONS

U.S. Appl. No. 29/543,437 of Akana et al., titled "Component for an Electronic Device," filed Oct. 23, 2015.

Primary Examiner — Austin Murphy

(74) *Attorney, Agent, or Firm* — Saidman DesignLaw Group, LLP

(57) **CLAIM**

The ornamental design for a component for an electronic device, as shown and described.

DESCRIPTION

FIG. 1 is a bottom perspective view of a component for an electronic device showing our new design;

FIG. 2 is a top perspective view thereof;

FIG. 3 is a front view thereof;

FIG. 4 is a right side view thereof;

FIG. 5 is a rear view thereof; and,

FIG. 6 is a left side view thereof.

The broken lines illustrate structure or features which form no part of the claimed design.
